MACHINE FOR MAKING MANIFOLD FORMS

Filed Sept. 2, 1936

FIG. 1

UNITED STATES PATENT OFFICE

2,144,331

MACHINE FOR MAKING MANIFOLD FORMS

George L. Fulk, San Francisco, Calif., assignor
to Carbon Interleaved Forms Corporation, Nor-
walk, Ohio, a corporation of Ohio

Application September 2, 1936, Serial No. 99,104

7 Claims. (Cl. 270—52)

This invention relates to a method and apparatus for making manifold register forms, in which carbons are utilized for making a record, and which are so arranged that they may be quickly removed from their position in the pack at the completion of the record. Manifold packs of this character generally comprise a plurality of record sheets interleaved with transfer sheets to form a single unit.

10 The general object of the present invention is to provide a method and apparatus for making a manifold package or pack of substantially continuous webs of material, at comparatively high rates of speed, and in such manner that accurate registration of the various webs will be maintained.

An additional object is to provide a machine for manufacturing manifold packs of substantially continuous rolls of material at comparatively high rates of speed, and which is arranged to assemble a plurality of webs, secure such webs together and sever individual packs from the webs without interrupting progress of the webs at any stage during the manufacture of the packs and in such manner as to maintain uniformity of width of the various packs, as well as to maintain uniformity of width of the various records in each pack.

Other and more specific objects of the present invention will become more apparent from the following description, reference being had to the accompanying drawing in which I illustrate a preferred form of mechanism for carrying out my improved method. The essential features of the invention will be summarized in the claims.

35 In the drawing, Fig. 1 is a side elevation of a machine embodying my invention; Fig. 2 is a fragmentary plan view of the machine, shown in Fig. 1; Fig. 3 is a fragmentary vertical section, the plane of which is indicated by the line 3—3 on Fig. 2, but shown on a larger scale than that illustrated in Fig. 2; and Fig. 4 is a view illustrating the manner in which the superimposed webs are assembled and severed.

40 The manifold pack with which the present invention is concerned may include any number of record strips, such as, for example, those indicated in Fig. 4 at 10, 11, 12 and 13, with interposed transfer or carbon strips 14, 15 and 16. 45 The record and transfer strips are fastened together, preferably with adhesive along one edge above perforation line 17, while the lower edges 18 of the transfer strips terminate above the bottom edges of the record strip. This arrangement 50 enables the operator to grasp the tab portion 20,

above the line of perforations 17 with the thumb and forefinger of one hand and the record strips in the region of the overhanging portion beneath the lowermost edges of the transfer sheets with the thumb and forefingers of the other hand. 5 The two portions are snapped apart, thus leaving the detached record strips of the unit in one hand and the detached transfer strips of the unit in the other hand, the transfer strips then may be discarded and the record strips filed for future 10 use.

To make the pack 21 illustrated in the extreme left-hand end of Fig. 4, I take rolls 30 of record strips or webs on which the desired forms have been printed, and I provide a series of openings 15 22 along the longitudinal edge of each strip. I utilize these openings for receiving projections on feeding rolls to hold the strips in registration during the assembling operation. The record strip rolls are indicated in Fig. 1 at 30 and are 20 each freely movable on a support, such as a bar 31. These bars are shown as extending laterally from a frame 32, and as corresponding in number to the number of record sheets required to form the desired pack.

25 The webs or strips are fed from their respective rolls 30 upwardly between suitable feeding rollers 33 and 34 which are power-driven by a motor 35. From its feed rollers, each web passes upwardly around suitable guide bars 37 and 38 30 after which it passes over a drum 40. The drums 40 each carry radially extending pins 41, that project into the openings 22 to align the longitudinal edge of each web as well as to align the printed form on one web with the printed forms 35 on the other web.

Suitable rolls 45 provided with recesses for receiving the pins 41 of the drums 40 are positioned above the respective drums and coat therewith to retain the web in position. Each roll 45 is 40 journaled at the free end of an arm 47, which is pivotally mounted on the frame, and is preferably arranged to permit adjustment of its position relative to its respective drum 40.

The transfer strips are inserted between the 45 record strips and to this end I have shown transfer strip rolls 50 journaled on suitable shafts 51, carried by the frame 32. The web from each transfer roll extends downwardly forming a loop 52, in which a weight 53 is cradled, thence upwardly to a guide bar 54, thence around the guide 38 of the associated record strip, from where it passes between the adjacent webs of record strips and over the respective drums 40.

The transfer strips and record strips are con- 55

nected together preferably by adhesive material. The adhesive material may be applied by paste rollers, which are journalled with their lower regions in paste containers 61, carried by the frame 32. Each paste roller has two contacting surfaces, one of which forms an adhesive line 58, by means of which adjacent record strips are fastened together, and the other of which forms a line 59, by means of which the back of each transfer strip is fastened to the back of the superimposed record strip. The upper edge 57 of the record strip terminates between the adhesive lines 58 and 59, while the adhesive line 58 is below the line of perforations 22.

15 After the record strips and the interposed transfer strips have been completely assembled and secured together as above described that portion of the record strips which carry the aligned openings 22, which are utilized merely 20 for maintaining the webs in accurate alignment and registration, is removed. This may be accomplished as indicated in Figs. 1 and 2, by a cutting wheel 70, which is constantly rotated by a motor 71 supported by the frame 32 in any 25 suitable manner. The wheel is preferably located, as shown in Figs. 2 and 3, to cut the webs immediately after they pass over an aligning roll 40a similar to the rolls 40 heretofore described. The assembled webs are maintained in contact 30 with the roll 40a by a spring pressed finger 45, as shown in Fig. 3.

Following the severing of the portions of the webs bearing the openings 22 from the assembled strips, as above described, the webs are severed to form individual packs 21. This severing is accomplished by the use of a shear carried by the rotating drum 80. This shear comprises a knife 81 secured to the roll 80, which in turn is drivingly mounted on a shaft 82 journalled in suitable bearings 83 carried by the frame 32 and is driven by the motor 35 as will be hereinafter more fully described.

40 As the assembled web passes under the rotating knife 70, it progresses along a table 84 the foremost edge of which is provided with a shear plate 85 arranged to coact with the knife 81 to shear a pack from the web once for every rotation of the drum 80.

45 The relation between the cutting edge of the knife and the drum 80 is such that the cutting edge rotates about the shaft 82 at substantially the same peripheral speed as the lineal speed of the assembled web. To enable this relationship to be maintained, both the shear plate 84 and the knife 81 are adjustably mounted.

50 The shear plate is mounted in a guideway 86 and an adjusting screw 87 is provided to facilitate the positioning of the plate. A clamping screw 88 passes through a slotted opening in the guideway and threadingly engages the shear plate table thus securing the shear plate in its adjusted position. Two sets of clamping and adjusting screws are preferably used, one at each side of the table 84 to enable accurate maintenance of the angular position of the shear plate 55 relative to the knife 81.

55 The knife 81 is mounted in a recess 90 formed in the roll 80 and is adjustable toward or away from the shear plate. Adjusting screws 91 carried by the drum and abutting the end of the knife facilitate this adjustment, while clamping screws 92, which pass through slotted openings in the knife and threadingly engage the drum, serve to maintain the knife in its adjusted position.

It will be noted that the rotary knife 70 which shears a strip carrying the openings 22 from the assembled web as well as the shear 81 which severs the web into individual packs, are both 5 relatively close to the guide drum 40a and are both arranged to perform their operations without interrupting the progress of the web or without causing the assembled web to buckle or to be otherwise distorted or forced out of alignment, any of which conditions would tend to 10 cause the widths of the various packs to vary one from the other or the widths of the individual records which make up a single pack to vary one from another.

15 The various aligning drums as well as the knife 81 are driven in synchronism to insure accurate registration of the records and to maintain constant width, both of the packs and of the records in each individual pack. As shown, the motor 35 is drivingly connected by a belt or 20 chain 100 with a line shaft 101. The drums 40 and 40a are each drivingly connected with respective worm gears 102 which mesh with worm 103 carried by the line shaft. The shaft 82 of the knife drum 80 is drivingly connected to a 25 worm gear 105 meshing with a worm 106 carried by a shaft 107 which is driven by the line shaft 101 through bevel gears 104. The feed rolls 33 and 34 may be driven from the line shaft 101 in a manner similar to that described in connection with the drums 40.

30 From the foregoing description it will be apparent that I have provided a method and apparatus by means of which multiple sheet forms may be expeditiously assembled by interleaving 35 webs of form material with webs of transfer material; securing the various webs together; and severing the assembled webs into packs without interrupting the progress of the materials at any stage of the operation thereby insuring accurate 40 registration of the records as well as maintaining accurate width of the packs and the various records of the individual packs.

I claim:-

1. The method of making a manifold pack in 45 which transfer strips are interleaved between record strips, comprising continuously feeding respective elongated strips of record and transfer material into interleaved relationship, at a predetermined rate of speed and aligning the strips 50 one to the other securing the aligned strips together adjacent one edge thereof, and subsequently cutting the strips transversely of their width while maintaining the movement of the strips at constant velocity.

55 2. The method of making a manifold pack in which transfer strips are interleaved between record strips, comprising continuously feeding elongated webs of record and transfer material 60 into interleaved relationship by moving the webs at a predetermined rate of speed and aligning the strips one to the other, securing the aligned webs together adjacent one edge thereof while they move at such predetermined rate of speed and subsequently moving a shear member at the same 65 rate of speed as the rate of travel of the webs to cause the shear to sever the webs into individual packs, while the webs move with constant velocity.

70 3. The method of making a manifold pack in 70 which transfer strips are interleaved between record strips comprising continuously feeding elongated webs of record strips having regularly spaced perforations adjacent one edge and transfer material into interleaved relationship by mov- 75

- ing the webs at a predetermined rate of speed and while progressively engaging the perforations to align one strip with another, securing the webs together while they move at such predetermined rate of speed, shearing the perforation bearing portion of the strips from the assembled webs and moving a shear member at the substantially same rate of speed as the rate of travel of the webs to cause the shear to sever the web into individual 10 packs without interrupting the speed of progress of the unsheared portions of the web and without interrupting the progressive engagement of the perforations in the unsheared portions of the web.
- 15 4. The method of making a manifold pack, in which transfer strips are interleaved between record strips, comprising continuously feeding elongated strips of record and transfer material into interleaved relationship, securing the strips 20 together along one edge thereof, subsequently cutting the strips along said secured edge, and finally cutting the strips transversely of said first cut to form individual packs, both of said cutting operations taking place without interrupting the 25 constant feeding of said elongated strips.
5. The herein described method of making a manifold pack, which comprises continuously feeding printed record webs having regularly spaced perforations adjacent one edge thereof 30 into interleaved relationship with transfer webs, passing said continuously moving webs over a roller having pins to engage said perforations whereby to align one printed web with another progressively securing the webs together, subse-

quently severing the perforation bearing portion of the secured webs, and finally shearing the continuously moving interleaved webs transversely of said first cut to form individual packs each of which comprise a plurality of secured sheets.

6. A machine for making manifold forms including means for supporting a plurality of rolls of record and transfer material, means for withdrawing strips of material from said rolls, guiding means for interleaving the transfer strips with record strips, means for moving the assembled web at a predetermined surface speed to keep the strips aligned one to the other, means for securing one edge of the aligned strips together, a rotating cutter arranged with its cutting edge 15 extending transversely of the web and substantially parallel with its axis, means to rotate said cutter at peripheral speed equal to the lineal speed of the travelling web, and relatively stationary means coacting with said cutter to shear 20 the assembled web into individual packs.

7. A machine for making manifold forms comprising means for assembling the forms in a continuous movement, means for cutting the forms into individual packs without interrupting the 25 movement of the forms, and mechanism for feeding and aligning the forms one to the other, means for securing one edge of the aligned forms together and means for operating the cutting mechanism to maintain uniformity of movement 30 of the uncut forms and to insure the cutting of each form to predetermined widths.

GEORGE L. FULK.
